Primary Examiner — Michelle E. Wilson(74) *Attorney, Agent, or Firm* — NSIP Law(57) **CLAIM**

We claim the ornamental design for a shoe care machine, as shown and described.

DESCRIPTION

FIG. 1 is a front perspective view of a shoe care machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front perspective view of the shoe care machine shown in an open position.

The broken lines in the figures depict portions of the shoe care machine which form no part of the claimed design.

1 Claim, 6 Drawing Sheets(56)
